US0D1092680S

(12) **United States Design Patent** (10) **Patent No.:** **US D1,092,680 S**
(45) **Date of Patent:** **** Sep. 9, 2025**

(54) **AERATION GRID**

(71) Applicant: **Advanced Drainage Systems, Inc.**,
Hilliard, OH (US)

(72) Inventors: **Adam Miller**, Haddam, CT (US);
Bryan Copes, Old Saybrook, CT (US); **Daniel J. Swistak**, Newmarket, NH (US); **Mark Youngclaus**, Waterford, CT (US)

(73) Assignee: **Advanced Drainage Systems, Inc.**,
Hilliard, OH (US)

(**) Term: **15 Years**

(21) Appl. No.: **29/918,472**

(22) Filed: **Nov. 28, 2023**

(51) LOC (15) Cl. **23-01**

(52) U.S. Cl.

USPC **D23/207**

(57) **CLAIM**

The ornamental design for an aeration grid, as shown and described.

DESCRIPTION

FIG. 1 is a top left perspective view for an aeration grid, showing the new design;

FIG. 2 is a top right perspective view thereof;

FIG. 3 is a bottom left perspective view thereof;

FIG. 4 is a bottom right perspective view thereof;

FIG. 5 is a left side elevation view thereof;

FIG. 6 is a right side elevation view thereof;

FIG. 7 is a front elevation view thereof;

FIG. 8 is a rear elevation view thereof;

(Continued)

FIG. 9 is a top plan view thereof; and,
FIG. 10 is a bottom plan view thereof.

1 Claim, 8 Drawing Sheets
